UNITED STATES PATENT OFFICE.

LAURENCE A. SCHNEIDER, OF CANTON, OHIO, ASSIGNOR TO CANTON FORGE & AXLE COMPANY, OF CANTON, OHIO, A CORPORATION OF DELAWARE.

METHOD OF MANUFACTURING SHEET-METAL RAIL ANCHORS.

Original application filed September 29, 1924, Serial No. 740,593. Divided and this application filed May 26, 1926. Serial No. 111,747.

My invention relates to improvements in the manufacture of rail anchors, and especially to the two-piece type of anchor having separately formed members for gripping opposite edges of the rail base, and having interlocking wedge flanges which, by their wedging engagement with each other, hold the anchor device in its operative position on the rail.

10 The primary object of the invention is to provide an improved method of forming two-piece anchors of the above type from sheet metal, whereby the anchor devices may be produced on a commercial scale, and whereby the 15 rail gripping jaws and the interlocking flanges of the anchor members may be made with a high degree of accuracy by bending operations.

A more specific object of the invention is to 20 provide an improved method of forming sheet metal rail anchors of the above type for bending metal blanks of sufficient thickness to provide the strength and rigidity required of devices of this character, and whereby the 25 bending of the blank may be effected with a minimum stretch of metal, even though the portion bent is relatively long and narrow.

In the drawings:

Fig. 1 is a plan view of a railroad rail 30 showing a two-piece anchor device constructed in accordance with my invention, applied to the base flange of the rail.

Fig. 2 is a face view of the rail anchor shown in Fig. 1, the base portion of the rail being 35 shown in section.

Fig. 3 is a view in perspective of one of the rail anchor members.

Fig. 4 is a view in perspective of another rail anchor member adapted to have an interlocking engagement with the members shown 40 in Fig. 3.

Fig. 5 is a plan view of a sheet metal blank, from which the member shown in Fig. 3 is formed.

45 Fig. 6 is a view showing the metal blank positioned between die members and subjected to an initial bending operation.

Fig. 7 shows the blank before it is subjected to the final bending operation.

50 Fig. 8 shows a metal blank after it is bent to its completed form.

Fig. 9 is a view in perspective of a sheet metal blank from which the anchor member shown in Fig. 4 is formed, a portion of the blank being illustrated in this figure as being 55 bent to a position to provide a tie abutment for the anchor.

Figs. 10 and 11 are views showing the blank positioned between die sections employed in connection with certain of the bending operations, and

Figs. 12 and 13 show the blank member and the apparatus employed in connection with the finishing operation of the anchor member.

My improved method is particularly suitable for use in the manufacture of a sheet metal anchor of the two-piece type shown in Figs. 1 to 4 inclusive of the drawings, but may obviously be used in connection with the manufacture of other types of anchors where 60 similar conditions are present.

The rail anchor illustrated in the drawings is a device consisting of two jaw members 10 and 11, which grip opposite edges of the rail base 13 and have a wedging interlocking 75 engagement with each other at a point beneath the base of the rail. The member 10 of the anchor is formed at one end with a jaw portion 14 adapted to grip one edge of the rail base, which jaw portion is so formed as to provide recesses 15 and 16 to provide clearance for the upper and lower corners of the rail base, and thereby insure a firm bearing engagement of the jaw 14 and the body portion of the member with the upper and lower surfaces, respectively, of the rail base.

The other end of the anchor is bent to provide a channel shaped portion 17, the upstanding flange 18 of which is relatively low and extends at an angle to the longitudinal 90 center of the rail so as to function as a wedge when the same is interlocked with the mating member 11. The flange 18 is preferably bent inwardly so as to stand at an angle to the vertical, and to provide a hook-shaped configuration. At a point intermediate the jaw and said channel shaped portion, a projection is bent downwardly to provide an abutment 19, adapted to bear against a vertical face of the cross-tie 20.

The member 11 is formed from a sheet metal blank of the configuration shown in Fig. 5,

bent to provide a jaw portion 21 for engaging the opposite edge of the rail. The jaw portion of this member, like the jaw portion of member 10, is formed with recesses 22 and 23 to provide clearance for the upper and lower corners of this edge of the rail base and thereby insures a firm contact of the jaw 21 and the body of the member with the upper and lower surfaces of the rail base at a point within the edges of the base. The extremity of the jaw 21 is also preferably curved upwardly, as shown at 24. The other end of the member 11 is formed with a downturned flange 25 of substantially the same height as the flange 18 and extends at an angle to the longitudinal axis of the rail so as to cooperate with the wedging surface of flange 18. The flange 25 is also inclined vertically so that the flanges 18 and 25 will provide an interlocking engagement to prevent the channel-shaped portion of the member 10 from moving downward with relation to the under-surface of the rail base. The member 11 is preferably made of slightly thicker material than the member 10 so as to provide a relatively thick portion or striking surface to receive the hammer blows during the application of the anchor to the rail.

The anchor is applied to the rail by hooking the jaws of members 10 and 11 over opposite edges of the rail base. The member 11 is then driven longitudinally of the rail so that the angularly disposed flanges 18 and 25 of the members will effect a firm wedging engagement with each other and thereby produce a tight gripping action of the jaws 14 and 21 upon the opposite edges of the rail base.

In carrying out my improved method in connection with the manufacture of member 11, a blank 26 is sheared from a metal sheet of suitable thickness by any suitable or preferred means, one end of the blank being sheared on a diagonal line, as shown in Fig. 5. The blank is then heated to a suitable bending temperature and is bent to a substantially V-shaped configuration, the diagonal edge 27 being bent downwardly on a line parallel to the diagonal edge to provide the inclined flange 25 of the anchor member. The preliminary bending of the blank 26 is preferably effected by means of die sections 28 and 29. The contour of the die sections is such that the point 30 of the die section 28 forms the clearance recess 23 of the member 11, shown in Figs. 2 and 3. During the initial bending operation, the diagonal edge 27 of the blank is bent over the rib 31 of the die 29 and is pressed firmly against its side 32 so as to form the inclined flange 25 of the anchor member. The curved surface 33 of die section 28 is so proportioned as to insure the pressing or swaging of the heated end 27 of the blank firmly against the surface 32 of the die section 29, and thereby insures a uniform in-

clination of the flange 25 of the finished member, and at the same time making it possible to bend said flange at a relatively sharp angle without appreciable stretch of the metal at the bend. The rib 31 of the die 29 is so disposed that the bending of the end 27 of the blank will be effected, as previously mentioned, along the line parallel to the diagonal edge of the blank. After the blank is bent to the configuration shown in Fig. 6, it is gripped between suitable gripping members to prevent distortion of the flanged end 34 and the portion 35, and the end 36 is then bent around an anvil of suitable configuration to form the jaw portion 21 of the anchor member.

In practice, the blank is removed from the dies 28-29, and is placed, as shown in Fig. 7, upon an anvil 37. The end of the anvil is formed with an enlargement, one portion 39 of which fits into the recess formed in the blank by the end 30 of the die 28. The other portion 40 of the enlargement at the end of the anvil forms a clearance recess 22 of the anchor member when the end 36 of the blank is bent to its completed form. Before bending the end 36 around the die, the gripping member 38 is pressed firmly against the blank to prevent distortion of the previously formed end portion. The end 36 is then bent around the die by means of the pivoted arm 41. The arm 41 operates on a curved track-way so that the downward movement of the arm from the position shown in Fig. 7 to the position shown in Fig. 8 brings the end 42 of the arm into engagement with the end 36 of the blank and presses it firmly against the curved under surface of the anvil.

The member 10 of the rail anchor shown herein is made from a blank 43 of the configuration shown in Fig. 9. The blank is sheared from a metal sheet of the desired thickness. The end 44 is formed with a diagonal edge and the edge 45 is formed with a portion 46. The blank is heated to a suitable bending temperature and is subjected while it is hot to a plurality of bending operations, all bending operations being preferably completed with a single heating of the blank. The first of the bending operations consists in bending the portion 46 to a position at right angles with respect to the body portion of the blank so as to provide the tie-abutting portion 19 of the anchor. The end 47 of the blank is then offset laterally with respect to the body portion 48, as shown in dotted lines in Fig. 10, and the end 49 is bent upwardly to the dotted line position shown in Fig. 10. The above bending operation, that is to say, the forming of the bends 50, 51 and 52 are effected preferably by means of die sections 53 and 54. The die sections are formed with cooperating faces of substantially the contour shown in Fig. 10. The blank is supported in a diagonal position on the shoulders 55 and

56 of die sections 54, so that the shoulders 57 and 58 of the die section 53 will engage the blank at substantially the same time and the bends 50, 51 and 52 are formed simultaneously. The pressure of the shoulders 55, 56, 57 and 58 of the dies upon opposite faces of the blank during the bending operation, tends to distribute the stretching of the metal throughout the entire length of the blank and thereby avoid excessive thinning of the metal at any one of the bends.

After the bends 50, 51 and 52 have been formed, the diagonal edge 44 of the blank is bent to form the interlocking flange 18 of the anchor member. The forming of the flange 18 is preferably accomplished by two bending operations. The first operation consists in bending the end 44 upwardly along a line parallel to the diagonal edge so that the width of the flange will be uniform throughout its length and so that the flange will extend at the desired angle to provide wedge shaped interlocking surfaces. The second operation consists in bending the partially formed flange 18 inwardly to its normal position, in which position it is adapted to interlock with the corresponding flange of the other member of the anchor.

The initial bending of the flange 18 is preferably effected by means of dies 59 and 60. The partially formed blank is positioned upon the die sections 59, in which position the end 44 of the blank rests on a curved shoulder 61 of the said die sections and bend 52 rests on a curved surface 62 of the die section 59. The die section 60 is provided with a projection 63 which, when the section 60 is moved downward, engages the angular portion 64-65 of the blank and presses it into a recess 66 of the die section 59 to partially form the channel shaped portion 17 of the anchor member. The projection 63 and the recess 66 taper in width so as to bend the flange 18 of the blank along a line parallel to the diagonal edge, as heretofore previously referred to. The other bends in the body portion of the blank are formed, it will be seen, on lines perpendicular to the longitudinal edges of the blank. The second bending operation in connection with the forming of the flange 18 is effected by means of mechanism shown in Figs. 12 and 13. The blank is removed from between the dies 59-60 and is placed in an inverted position on an anvil 67. The anvil is formed at one end with a portion 68 corresponding in contour to the inner wall of the channel shaped portion 17 of the finished anchor member, and is formed at the other end with a curved portion corresponding substantially to the contour of the jaw end of the anchor member. The end 44 of the blank is bent inwardly and pressed firmly against the wall 69 of the anvil, by means of a dog 70 or other suitable means for bending the flange 18 inwardly throughout its entire length without effecting displacement of metal likely to vary the width of the flange. The dog or other gripping member 70 is held in its blank gripping position during the subsequent bending of the blank, so as to prevent the subsequent pressures against the blank from distorting the angularity of the flange. The end 71 of the blank is bent around the end 72 of the anvil to provide the jaw portion 14 of the finished anchor member. This end of the anvil is formed with beads 73-74 which provide for the forming of the clearance recesses 15 and 16, respectively, of the anchor member. The bending of the end 71 of the blank is accomplished by means of a pivoted arm 75, formed with a rounded angularly disposed portion 76 and is guided in its movement on a cam surface 77 so that the end of the arm will engage the end 71 of the blank and bend it around the curved under surface of the anvil. The body portion of the blank is also subjected to pressure during the bending of the end 71 so as to insure that the blank when bent to its completed form will conform to the curvature of the anvil. The blank is shown in Fig. 13 in its completed form and is held firmly on the anvil after it has been bent from the position shown in Fig. 12 to the position shown in Fig. 13.

While I have described my improved method as consisting of certain definite steps to be carried out in the manufacture of a rail anchor of the type shown in the drawings, it will be understood that I contemplate as a part of my invention, all deviations in practice of the method as come within the scope of the appended claims.

This application is a division of my copending application Serial No. 740,593, filed September 29, 1924, which has matured into Patent No. 1,644,283 dated October 4, 1927.

I claim:

1. The method of making a rail anchor member of sheet metal comprising the shearing of a metal blank along lines providing a diagonal edge at one end of the blank, providing the blank with reverse bends, one of which is parallel to said diagonal edge to provide an angularly disposed flange, and bending the other end of the blank along a plurality of parallel lines to provide a rail engaging jaw.

2. The method of making a rail anchor member comprising the bending of a blank along a diagonal line to provide an angularly disposed flange, bending the blank on a line perpendicular to the side edges thereof to provide a recess extending below the plane of that portion of the blank between said bends to provide clearance for the longitudinal edges of the rail base flange, then bending one end of the blank to provide a hook shaped configuration.

3. The method of forming a two-piece rail anchor of sheet metal, comprising the shearing of two metal blanks along lines providing

each blank with a diagonal edge at one end thereof, bending one of said blanks to provide portions offset laterally with relation to each other, bending said blank along a line parallel to said diagonal edge to provide a flange, pressing said flange inwardly to a hook shaped configuration, bending the other end of said blank to provide a jaw portion, form-

ing the other blank with reversed bends, one of which is parallel to its diagonal edge to provide a flange to interlock with the said flange of the other member, then bending the other end of the blank to a hook shaped configuration. 10

LAURENCE A. SCHNEIDER.
